PORTABLE PITCHER'S MOUND

John J. Goeders, Altoona, Iowa, assignor to
True-Pitch, Inc., Altoona, Iowa

Filed Sept. 11, 1972, Ser. No. 287,675

Term of patent 14 years

Int. Cl. D21—02

U.S. Cl. D34—5 GP

FIG. 1

FIG. 2

FIG. 3

FIG. 4

FIG. 1 is a top perspective view of a portable pitcher's mound showing my new design;

FIG. 2 is a top plan view thereof;

FIG. 3 is an elevational view taken from one side thereof;

FIG. 4 is a characteristic front or rear elevational view as taken from either the right hand side or the left hand side of FIG. 3.

I claim:

The ornamental design for a portable pitcher's mound, substantially as shown and described.
